UNITED STATES PATENT OFFICE

ARTHUR W. BURKS, OF DECATUR, ILLINOIS

CENTRIFUGAL PUMP

Application filed June 28, 1930. Serial No. 464,002.

The present invention relates to pumps and more particularly to pumps of the centrifugal type. In my Patent 1,619,286, issued March 1, 1927, there is disclosed a rotary pump which includes a rotor having adjacent its margin an annular series of buckets which serve to propel fluid through a substantially circular raceway from an inlet to an outlet, there being a substantially water-tight fit at opposite sides of the raceway.

The present invention relates to pumps of this type and has as an object to provide a pump of this character with a multiplicity of raceways arranged in a novel manner and cooperating with a rotor of different construction.

A further object of the invention is to provide a pump having a plurality of longitudinally arcuate raceways each having an inlet and an outlet independent of the inlet and outlet of the other and arranged preferably in a common plane with radii of curvature of the same length. The invention also seeks to provide in association with such a raceway arrangement, a rotor of novel construction having an annular series of blades adapted to traverse both raceways from their inlets to their outlets and also having a plurality of peripherally directed passages which serve to direct a high velocity liquid discharge toward these raceways. For this purpose there is provided a primary raceway adapted to receive the centrifugal discharge from the rotor passages and to direct the fluid into both of the first mentioned raceways.

A further object of the invention is to provide a pump of this character having associated therewith means for forming a liquid whirlpool adapted to separate air by centrifugal force as disclosed in my Patent 1,686,549, granted October 9, 1928. The invention aims to provide adjacent each inlet for the longitudinally arcuate raceways and adjacent each outlet a pocket adapted to set up a liquid whirlpool which separates air from the liquid by centrifugal force.

The foregoing and other objects and features of the invention will become clearer as the description proceeds in connection

with a preferred embodiment disclosed in the accompanying drawings. In these drawings:

Figure 1 is a vertical sectional view on the line 1-1 of Figure 2.

Figure 2 is a vertical sectional view on the line 2-2 of Figure 1.

Figure 3 is a sectional view on the line 3-3 of Figure 2.

Figure 4 is a face view of the raceway section of the pump.

Figure 5 is a face view of the opposite side of the raceway section.

Figure 6 is a sectional view on the line 6-6 of Figure 2.

Figure 7 is a sectional view on the line 7-7 of Figure 2, and

Figure 8 is a face view of the rotor partly broken away.

Referring to the drawings for a more detailed description, 10 indicates a portion of a pump casing having secured thereto, as by cap screws 11, a second section 12, the two sections being of substantially uniform diameter and serving to clamp therebetween a plate-like raceway section 13 of somewhat smaller diameter than the first mentioned sections, so that its marginal portion may fit and be clamped between a shoulder 14 on the section 12 and a shoulder 15 on the casing section 11. The raceway section 13 has formed on a lateral face a plurality of raceways 16, 17, each of which is longitudinally arcuate and also arcuate in cross section, as shown in Figure 1. The raceway 16 extends from an inlet opening 18 to an outlet opening 19 and the raceway 17 from an inlet opening 20 into an outlet opening 21.

The two raceways are disposed in a common plane and have radii of longitudinal curvature which are of the same length, with the result that the two raceways form together substantially a complete circle which is interrupted only by the space between the adjacent inlet opening and outlet openings of the respective raceways. Each space is substantially filled by a cut-off web 22, which serves to minimize the passage of fluid from the outlet opening of one raceway to the inlet of the other. The cut-off webs lie substan-

tially flush with the ends of blades 23 on the rotor 24, the blades forming therebetween an annular series of buckets adapted to propel liquid through the raceways. As will be observed, the rotor and raceway section are provided, at radially opposite sides of the raceways and buckets, with complementary ribs and grooves 25 which inter-fit and form a substantially fluid-tight seal, although if desired the ribs may be notched to permit passage from the raceway into the grooves of a very slight amount of liquid sufficient to minimize friction between opposed surfaces. The rotor 24 is actuated by means of a shaft 26 to which the rotor is connected, the shaft extending outwardly through a stuffing box 27 and a bearing 28 formed in arms 10' cast with the pump section 10.

As will be understood, operation of the rotor will serve to propel fluid through the raceways 16, 17 in the direction of the arrows A. The liquid which is discharged through the outlet opening 20 enters a discharge chamber formed in the section 12. This chamber is of irregular formation and comprises an upper pocket 29 disposed at the outlet opening 19 and a lower pocket 30, the two pockets being connected by means of a substantially circular channel 31 disposed between a circular inner wall 32 and an outer wall 33 of similar formation. The passage communicates with the lower pocket 30 through an opening 34 formed in the outer wall and with the upper pocket 29 through an opening 35 formed in the outer wall 33. One of the pockets, in the present instance the upper pocket 29, has a discharge line connection 36 for discharge of liquid or air, or both, from the pump. This discharge connection is, therefore, in communication with both pockets of the chamber, in the present instance directly with the pocket 29 and through the latter with the pocket 30. Liquid discharged into the two pockets through the outlet openings 19, 21, sets up a liquid whirlpool indicated by the arrows W in Figure 6. These whirlpools tend to separate air by centrifugal force and the liquid of the whirlpool due to its location adjacent the buckets, to the path of which the whirlpool is tangential, engages the buckets and displaces therefrom into the whirlpool air contained in the buckets. Further description of this feature of the invention is thought unnecessary since the general operation of the whirlpool is set forth in my Patent 1,686,549, granted October 9, 1928. It will be understood, however, that any liquid which may be carried away from either whirlpool as the buckets leave the discharge openings will be carried into the other raceway and after passing through the latter will be discharged through the outlet opening of the second raceway. Although the cut-off webs 22 serve to keep this liquid at a minimum, a small amount will necessarily be carried away

from each whirlpool, but an equivalent amount will be supplied thereto in the manner described.

Moreover, the manner in which the liquid passes through each of the raceways 16, 17 in a helical path repeatedly entering and leaving the buckets need not be here described, since it is fully set forth in my Patent 1,619,286, granted March 1, 1927. The path of travel of the liquid in each of the raceways 16, 17 is identical with that described in said patent, the only difference between the raceways being that in the form of the present application they are somewhat shorter. Each raceway is, however, cross sectionally 75 80 85 arcuate on radii substantially the same as the radii of curvature of the bucket bottoms in the rotor, whereby the walls of the buckets and raceways merge and do not interfere with the whirling or helical movement of the liquid as it passes through the raceways.

The liquid is not supplied directly to the raceways as in the above mentioned patent, but according to the present invention has imparted thereto, preferably by the same rotor, 90 a considerable velocity and pressure before entering the raceways. For this purpose the rotor is formed with a plurality of peripherally directed passages 38 formed between the substantially radially disposed webs 39. 95 These webs serve to connect a rear wall 40 of the rotor and a wall 41 curved in cross section and carrying the buckets on one lateral face.

The rear surface of the wall 41 is curved toward the same face of the rotor, so that liquid 100 centrifugally discharged through the passages 38 will be laterally directed adjacent the periphery of the rotor. Intermediate the webs 39 are shorter webs 39' which serve to divide the passages adjacent the periphery 105 into a plurality of buckets or outlets 44. These outlets direct the fluid into a raceway 45 formed on the raceway section 13 and radially spaced outwardly from the raceways 16, 17. Liquid may enter the passages 38 at 110 substantially the center of the rotor through opening 46 which surrounds the axis of the rotor and is in communication with a supply chamber 47 formed by the inner wall 32 of the annular passage 31.

The supply chamber 47 receives fluid from a supply connection 48 and there is disposed between the latter and the chamber 47 a substantially tubular strainer 49, so that foreign matter in the liquid may not reach the rotor. 115 This liquid after passing through the chamber 47 into the rotor passages 38 is discharged centrifugally into the radially spaced raceway 45.

The raceway 45 communicates through 120 outlet openings 50, 51 with pockets 52, 53 formed in the pump section 12 at the inlet openings 18, 20, the pockets communicating, respectively, with the raceways 16, 17. In other words, the pockets 52 and 53 are in 125 130

communication with the raceways 16 and 17 through the inlet openings 18, 20 and also with the raceway 45 from which liquid is discharged into the pockets through openings 50, 51. Liquid enters the pockets 52, 53 in a substantially tangential direction, as illustrated in Figure 7, and forms an air-separating liquid whirlpool, the path of the liquid in the whirlpool being generally indicated by the arrows 'W' in Figure 7. These whirlpools in the pockets 52, 53 operate in a manner similar to the whirlpools in the pockets 29, 30 and serve to separate air from the liquid as well as to displace into the whirlpools the contents of the open mouths or buckets 44 at the ends of the centrifugally discharging passages 38 in the rotor.

The rear face of the raceway section at the various outlet and inlet openings is bevelled to provide surfaces 55 which permit the paths of the whirlpools in the several pockets to closely approximate the paths of travel of the buckets 23 and 44 on the rotor, thereby insuring an engagement of the whirling liquid with the buckets on the rotor and the displacement of any gaseous content of the buckets into the liquid whirlpools.

The tubular strainer 49 may be readily removed without disturbing the supply connection 48, since it is supported beneath an entrance chamber 59 which has a lower wall formed with an opening 60 permitting the liquid to pass to the interior of the strainer. The lower end of the strainer is closed by a cap 61 which is supported at an opening 62 by means of a removable plate 63. The plate 63 has one end resting upon a lug 64 and its other end is fastened as by means of a cap screw 65 to the wall of the section 12. To clean or replace the screen 49, it is simply necessary to disconnect the plate 63 and the screen may then be lowered through the opening 62. The entrance chamber 59 may be inspected, as for the purpose of determining whether the strainer should be cleaned, through a port 66 normally closed by a threaded plug 67. This port also serves the purpose of priming the pump should, for any reason, the whirlpool pockets 29, 30, 52, 53 become empty. Ordinarily, however, these pockets will serve to retain a sufficient amount of fluid to cause evacuation of air from the supply line and initiate liquid pumping.

Obviously, numerous modifications may be made in the structure illustrated and described without departing from the invention, the essential features of which are set forth in the following claims.

60 I claim:

1. In a pump of the class described, a plurality of longitudinally arcuate raceways each having an inlet opening and an outlet opening, a radially spaced raceway having openings leading therefrom to said inlet

openings, a rotor having a series of buckets adapted to traverse said arcuate raceways and having a series of peripherally directed and centrifugally discharging passages independent of said buckets emptying into said last-mentioned raceway, means for introducing liquid into said rotor passages, and means for discharging from the pump liquid which passes through the outlet openings of said first-mentioned raceways.

2. In a pump of the class described, a plurality of longitudinally arcuate raceways with radii of curvature of substantially equal length each having an inlet opening and an outlet opening, a radially spaced raceway having openings leading therefrom to said inlet openings, a rotor having a series of buckets adapted to traverse said arcuate raceways and having a series of peripherally directed and centrifugally discharging passages independent of said buckets emptying into said last-mentioned raceway, means for introducing liquid into said rotor passages, and means for discharging from the pump liquid which passes through the outlet openings of said first-mentioned raceways.

3. In a pump of the class described, a plurality of longitudinally arcuate raceways each having an inlet opening and an outlet opening, a raceway spaced radially outwardly from said first-mentioned raceways and having openings leading therefrom to said inlet openings, a rotor having a series of buckets adapted to traverse said inner raceway and having a series of peripherally directed and centrifugally discharging passages independent of said buckets and emptying into said outer raceway, means for introducing liquid into said rotor passages, and means for discharging from the pump liquid which passes through the outlet openings of said inner raceways.

4. In a pump of the class described, a plurality of longitudinally arcuate raceways having radii of curvature of substantially equal length in a common plane and each having an inlet opening and an outlet opening, a raceway spaced radially outwardly from said first-mentioned raceways and having openings leading therefrom to said inlet openings, a rotor having a series of buckets adapted to traverse said inner raceway and having a series of peripherally directed and centrifugally discharging passages independent of said buckets and emptying into said outer raceway, means for introducing liquid into said rotor passages, and means for discharging from the pump liquid which passes through the outlet openings of said inner raceways.

5. In a pump of the class described, a plurality of longitudinally arcuate raceways each having an inlet opening and an outlet opening, a raceway radially spaced from said first-mentioned raceways and having open-

ings leading therefrom to said inlet openings, a rotor having a series of buckets adapted to traverse said arcuate raceways and having a series of peripherally directed and centrifugally discharging passages independent of said buckets and emptying into said spaced raceway, means for introducing liquid into said rotor passages, and means for discharging from the pump liquid which passes through the outlet openings of said arcuate raceways, said last-mentioned means including a pocket disposed at each outlet opening and adapted to form a liquid air-separating whirlpool and said pockets being in communication with one another.

6. In a pump of the class described, a plurality of longitudinally arcuate raceways each having an inlet opening and an outlet opening, a raceway spaced from said first-mentioned raceways and having openings leading therefrom to said inlet openings, a rotor having a series of buckets adapted to traverse said arcuate raceways and having a series of peripherally directed and centrifugally discharging passages independent of said buckets and emptying into said spaced raceway, means for introducing liquid into said rotor passages, means for discharging from the pump liquid which passes through the outlet openings of the radially inner raceways, said last-mentioned means including a pocket disposed at each outlet opening and adapted to form a liquid air-separating whirlpool, and a discharge connection in communication with both of said pockets, with one directly and the other through the first-mentioned pocket.

7. In a pump of the class described, a plurality of longitudinally arcuate raceways arranged in substantially a common plane and each having an inlet opening and an outlet opening, a raceway spaced radially from said first-mentioned raceways and having discharge openings leading therefrom to said inlet openings, pockets formed at said inlet openings into which the last-mentioned openings empty and each adapted to form a liquid air-separating whirlpool, a rotor having a series of buckets adapted to traverse said arcuate raceways and having a series of peripherally directed and centrifugally discharging passages independent of said buckets and emptying into said spaced raceway, means for introducing liquid into said rotor passages, and means for discharging from the pump liquid which passes through the outlet openings of said arcuate raceways.

8. In a pump of the class described, a plurality of longitudinally arcuate raceways with uniform radii of curvature and each having an inlet opening and an outlet opening, a raceway spaced from said first-mentioned raceways and having discharge openings leading therefrom to said inlet openings, pockets formed at said inlet openings

into which the discharge openings empty, each pocket being adapted to form a liquid air-separating whirlpool, a rotor having a series of buckets adapted to traverse said arcuate raceways, and having a series of peripherally directed and centrifugally discharging passages independent of said buckets and emptying into said spaced raceway, means for introducing liquid into said rotor passages, and means for discharging from the pump liquid which passes through the outlet openings of said arcuate raceways, said last-mentioned means including a pocket disposed at each outlet opening and adapted to form a liquid air-separating whirlpool, and a discharge connection in communication with both of said pockets, with one directly and the other through the first-mentioned pocket.

9. In a pump of the class described, a plurality of longitudinally arcuate raceways each having an inlet opening and an outlet opening and another raceway spaced from said first-mentioned raceways and having an opening leading therefrom, means for exchanging liquid between said spaced raceways after it has traversed one of the raceways, means for discharging the exchanged liquid after it has traversed a separated raceway, means for introducing liquid into one of said raceways, and a rotor having a series of buckets adapted to traverse said first-mentioned raceways and having a plurality of peripherally directed centrifugally discharging passages emptying into the second-mentioned raceway.

10. In a pump of the class described, a raceway portion having on a lateral face a plurality of longitudinally arcuate raceways each having an inlet opening and an outlet opening both of which extend through the portion to the opposite lateral face and another raceway radially separated from said first-mentioned raceways and having an opening leading therefrom, means for exchanging liquid between said radially spaced raceways after it has traversed one of the raceways, means for discharging the exchanged liquid after it has traversed a second and radially separated raceway, means for introducing liquid into one of said raceways and a rotor having a series of buckets adapted to traverse said first-mentioned raceways, and also having a plurality of peripherally directed centrifugally discharging passages emptying into the second-mentioned raceway.

11. In a pump of the class described, a plurality of longitudinally arcuate raceways each having an inlet opening and an outlet opening, another raceway radially separated outwardly from said first-mentioned raceways and located in a section having an opening leading from the raceway to the opposite lateral face of the section, means for exchanging liquid between said radially spaced race-

ways after it has traversed one of the raceways, means for discharging the exchanged liquid after it has traversed a second raceway, means for introducing liquid into one of said raceways, and a rotor having a series of buckets adapted to traverse said first-mentioned raceways and having a plurality of peripherally directed centrifugally discharging passages emptying into the second-mentioned raceway.

12. In a pump of the class described, a raceway portion having on a lateral face a plurality of longitudinally arcuate raceways each having an inlet opening and an outlet opening both of which extend through the portion to the opposite lateral face and another raceway radially separated outwardly from said first-mentioned raceways and having an opening leading therefrom to the opposite lateral face of the portion, means for exchanging liquid between said radially spaced raceways after it has traversed one of the raceways, means for discharging the exchanged liquid after it has traversed the second raceway, means for introducing liquid into one of said raceways, and a rotor having a series of buckets adapted to traverse said first-mentioned raceways and also having a plurality of peripherally directed centrifugally discharging passages emptying into the second-mentioned raceway.

13. In a pump of the class described, a plurality of longitudinally arcuate raceways having radii of uniform length in a substantially common plane, each raceway having an inlet opening and an outlet opening, a rotor having a series of buckets traversing said raceways, means for discharging from the pump liquid propelled through said outlet openings, and means for directing liquid simultaneously into said raceways through said inlet openings, said last-mentioned means including a plurality of peripherally directed and centrifugally discharging passages in said rotor adapted to initially receive fluid, a raceway into which said buckets empty and connections between said raceway and the inlets for said first-mentioned raceways.

14. In a pump of the class described, a plurality of longitudinally arcuate raceways disposed in a substantially common plane, each raceway having an inlet opening and an outlet opening, a rotor having a series of buckets traversing said raceways, means for discharging from the pump liquid propelled through said outlet openings, and means for directing liquid simultaneously into said raceways through said inlet openings, said last-mentioned means including a plurality of peripherally directed and centrifugally discharging passages in said rotor adapted to initially receive fluid, a raceway into which said buckets empty and connections between said raceway and the inlets for said

first-mentioned raceways, said connections including a pocket disposed at each of said inlet openings, and a pair of openings formed in said last-mentioned raceway through which the latter discharges into said pockets. 70

15. In a pump of the class described, a raceway section having on one lateral face a plurality of longitudinally arcuate raceways each having an inlet opening and an outlet opening both of which extend through the section to the opposite lateral face, a casing section at each side of said raceway section between which the raceway section is held in position by the clamping action of the two casing sections, a rotor in one of said sections having a series of buckets traversing said raceways, the other section having an inlet chamber in communication with both raceways through said inlets, and also having a discharge chamber for receiving fluid discharged through said outlets. 75 80 85

16. In a pump of the class described, a raceway portion having on a lateral face a plurality of longitudinally arcuate raceways having radii of equal length in a common plane and each having an inlet opening and an outlet opening, which extend through the portion to the opposite lateral face, a radially outer raceway separated from said first-mentioned raceways and having a pair of outlet openings extending through the portion to the opposite lateral face, a pocket at each of said inlet openings adapted to receive liquid discharged through the outlet openings of said radially outer raceway and to direct the same into said radially inner raceways through their inlet openings, a pocket at each of said outlet openings for said inner raceways, each pocket being adapted to form a liquid air-separating whirlpool, a discharge connection for liquid discharged from the radial inner raceways and in communication with said pockets at their outlet openings, and a rotor having a series of buckets traversing said radially inner raceways and a series of peripherally directed centrifugally discharging passages emptying into said outer raceway, complementary surfaces on said rotor and raceway section sealing said raceways one from another, and means for introducing fluid into said rotor passages. 90 95 100 105 110 115

In testimony whereof I have hereunto set my hand.

ARTHUR W. BURKS. 120
